JAMES ALWARD SEYMOUR, OF AUBURN, NEW YORK.

INTERNAL-COMBUSTION MOTOR.

1,175,018.

Specification of Letters Patent. Patented Mar. 14, 1916.

Application filed June 14, 1913. Serial No. 773,598.

To all whom it may concern:

Be it known that I, JAMES ALWARD SEYMOUR, a citizen of the United States, residing at Auburn, Cayuga county, New York, have invented certain new and useful Improvements in Internal-Combustion Motors, of which the following is a full, clear, and exact description.

My invention relates to internal combustion motors of the two-stroke cycle valveless type having a differential piston in which the functions of an exhaust valve and of an inlet or scavenging valve are performed by the opening and closing of ports by the movement of a differential working piston, said ports being located in the proper position in the cylinder wall and in a tubular extension of the said differential piston respectively.

Among the main objects of the invention are simplicity, compactness, convenience of construction, fewness of parts, increased efficiency of scavenging, and an arrangement of parts whereby the stresses of the various parts of the motor are more suited to the materials of which they are usually composed than now exists in motors of the ordinary construction of this general class.

In the accompanying drawings: Figure 1 is a longitudinal section of the cylinder end of a motor showing conventionally only such parts as are essential to a full understanding of the invention. Fig. 2 is a corresponding view of a modification.

In Fig. 1, C represents the working cylinder. P represents the large part of a differential working piston, while R represents the smaller part or tubular extension of said piston. A suitable connection may be provided between the piston and a crank shaft (not shown), for example, an ordinary connecting rod X. The exhaust ports are shown at E. The inlet or scavenging ports are shown at S as leading from the interior of the piston extension R into the cylinder C when the piston stands in one position. The scavenging pump is formed by a scavenging piston A mounted upon the piston extension R and by a cylinder T in which the scavenging piston moves, which cylinder is of larger diameter than the working cylinder and may be conveniently formed as an extension of the working barrel of the cylinder C enlarged or preferably of its water jacket wall W. The scavenging pump cylinder T has an inlet or suction valve I,

which may be either automatically or positively operated, as desired. It is preferable however to connect the pump cylinder T with the ports S through the passage or passages V leading to the interior of the piston extension R. In this case, the clearance space within the scavenging pump cylinder T should be made large enough, as compared with the displacement of the piston A, 65 to keep the scavenging pressure down to the desired amount upon the opening of the ports. The ports S perform the dual function of discharge passages for the scavenging pump cylinder T and air admission 70 passages for the main cylinder C. By thus doing away with a separate air reservoir for holding a supply of scavenging air, higher initial scavenging pressure can be secured with the same amount of work performed in 75 the scavenging pump cylinder T, although this pressure will rapidly fall away upon the opening of the ports S. This falling away, however, is not objectionable in this particular instance because the scavenging 80 of the cylinder C is done in a very short space of time, and the chief thing to be accomplished is to provide a sufficiently high pressure of scavenging air at the beginning 85 of the scavenging operation, to overcome 90 the inertia of the gases to be expelled from the cylinder in a short time. When these gases are once in motion, a rapidly falling pressure will not affect unfavorably the scavenging function. K represents a fuel 90 injection inlet.

In the modification shown in Fig. 2, I show the same arrangement of parts as in Fig. 1, excepting that the position of the working cylinder C' and the scavenging 95 cylinder T' are reversed, bringing the scavenging pump nearer to the crank shaft end of the motor. In this view r represents a tension rod that may pass through the interior of the piston P' and its extension R', if desired. X' represents the connecting rod, in this instance connected to the tension rod r and pivoted adjacent the scavenging pump end of the tubular extension of the working piston. A' represents the scavenging pump piston and T' represents the scavenging pump cylinder. In this arrangement, the scavenging pump piston A' serves as a cross head for the connecting rod X' and possesses advantages 105 over the trunk form of main piston shown in Fig. 1, wherein the side thrust due to the

angularity of the connecting rod is taken against the hot working cylinder wall instead of against a relatively cool wall. K' represents the fuel injection inlet. The arrangement shown in Fig. 2 has a great advantage in connection with this valveless type of motor in securing a superior distribution of strains. The running parts which, aside from the working piston, are usually and preferably made very light and of some material of great tensile strength, are subject only to tension, for which, in view of their slenderness and great strength, they are much better adapted for than for compression stresses. The frame of the motor, on the other hand, which is usually and preferably made of cast iron, in this arrangement is subject only to compression stresses, to which, by reason of the character of the material and the large moment of inertia of its cross section, it is best adapted.

In the ordinary motor of the usual type it is usual and customary, in order to avoid an objectionable piston rod stuffing box in the cylinder, that the running parts be always in compression and the frame always in tension, although owing to the materials of which they are usually made, they are respectively poorly suited to such stresses. The proposed arrangement shown in Fig. 2 involves a very much lighter and cheaper construction, as well as a smoother running construction, by reason of the better adaptation of the form and material of the frame and running parts to the stresses to which they are respectively subjected.

In the operation of the motor as shown in Fig. 1, the piston P is shown at the end of its working stroke. The exhaust port E is open, as is also the inlet port S. The cylinder C has been emptied of its burned gases by the discharge of the contents of the scavenging cylinder T through passage V, tubular extension R, and ports S, which latter open directly into the main cylinder C so as to permit the latter to be filled with a charge of fresh air. Upon the beginning of the return stroke of the piston, the ports S and E are closed and valve I opened, admitting air into the pump cylinder T. On the said return stroke, the air in the working cylinder C is compressed. At about the beginning of the working stroke, fuel may be injected through the inlet K and ignited by any suitable means, preferably by compression, whereby the burning of the fuel will cause internal expansion, forcing the piston P forwardly on its working stroke. During the latter part of the working stroke, the burned charge continues to expand doing work. On this working stroke the suction valve 1 is closed so that when said stroke is completed to the extent of opening the valves S and E, the compressed air in the scavenging pump cylinder

will rush into the working cylinder to expel the inert or burnt gases.

The operation of the engine shown in Fig. 2 is substantially similar, excepting that the working parts are always in tension and the frame is always in compression, instead of vice versa, as in Fig. 1. The parts of Fig. 2 not already identified by reference characters which correspond to the parts shown and described in Fig. 1 include the suction valve 1', the exhaust ports E', the scavenging ports S' and V'. The inlet ports E as shown are preferably so arranged or proportioned that they will open slightly in advance of the opening of the ports S into the working cylinder C. It will be observed that the cylinder C has a head portion which is contracted and suitably proportioned to guide the piston extension R, the usual packing rings such as provided in engines of this internal combustion variety being provided wherever such devices may be employed with good effect, there being no novelty claimed in the use of such devices in the present case. For convenience of expression we will refer to the arrangement of the working cylinder and the pump cylinder and their respective pistons as being a tandem arrangement.

What I claim is:

1. In an internal combustion motor of the high compression fuel burning type, a working cylinder, a differential piston arranged to reciprocate in said cylinder, the smaller part of said piston comprising a tubular extension, a fuel injection inlet in said cylinder, a scavenging pump cylinder arranged in tandem with the working cylinder, a scavenging pump piston carried by the tubular extension of the working piston and moving in said pump cylinder, an air inlet valve in communication with the scavenging pump cylinder, an air passage leading from the scavenging pump cylinder through the tubular extension and into the working cylinder including ports in the side of the tubular extension arranged to open into the working piston cylinder when the piston is near the end of its working stroke, an exhaust port in the wall of the working cylinder arranged to be opened and closed by the larger part of the working piston when the latter is near the end of its working stroke, and a connecting rod connected with said working piston, said fuel injection inlet being in the end of said working cylinder which is adjacent to said pump cylinder.

2. In an internal combustion motor of the high compression fuel burning type, a working cylinder, a differential piston arranged to reciprocate in said cylinder, the smaller part of said piston comprising a tubular extension, a fuel injection inlet in said cylinder, a scavenging pump cylinder arranged

in tandem with the working cylinder, a scavenging pump piston carried by the tubular extension of the working piston and moving in said pump cylinder the working surfaces of said pistons facing toward one another, an air inlet valve in communication with the scavenging pump cylinder, an air passage leading from the scavenging pump cylinder through the tubular extension and 5 into the working cylinder including ports in the side of the tubular extension arranged to open into the working piston cylinder when the piston is near the end of its working stroke, an exhaust port in the wall of 10 the working cylinder arranged to be opened 15 and closed by the larger part of the working piston when the latter is near the end of its working stroke, and a connecting rod connected with said working piston and pivoted adjacent the end of the tubular extension 20 of the said working piston upon which the scavenging pump piston is mounted and being under tension during the working movement of said differential piston, substantially as described.
